(57) **CLAIM**

The design for the furniture leg, as shown and described.

DESCRIPTION

FIG. 1 is a perspective view of a furniture leg, showing my new design; the broken lines are for environmental purposes only and form no part of the claimed design.

FIG. 2 is a front view of the furniture leg;

FIG. 3 is a left view of the furniture leg;

FIG. 4 is a rear view of the furniture leg;

FIG. 5 is a top view of the furniture leg; and,

FIG. 6 is a bottom view of the furniture leg.
